RIVET

Francis L. Sheane, Shelton, Conn., assignor to
Shelton Tack Company, Shelton, Conn., a corporation of Connecticut

Application December 18, 1935, Serial No. 54,984

3 Claims (Cl. 85—37)

This invention relates to rivets.

More particularly the present invention relates to a rivet provided with a downwardly converging head and with means for gripping the material with which it becomes intimately associated when in use.

A primary object of the invention is to provide a rivet that will allow distribution of stresses on the material intimately associated therewith over substantially the entire area comprehended by the under-surface of the rivet head rather than merely to the portion of the material immediately adjacent the rivet shank; also, to provide means for exerting a drawing force on the material intimately associated with the under-surface of the rivet head, inward toward the rivet shank to counteract the tendency otherwise inherent in such downwardly converging head of exerting compressive forces outwardly on the material therewith associated.

Embodiments of the present invention include a rivet having gripping means concentrically arranged on the under-surface of its downwardly converging head.

In preferred forms such gripping means takes the shape of a plurality of annular ridges concentrically arranged on the under-surface of the rivet head from the outer diameter of the rivet shank outward to the periphery of the rivet head, each set of annular ridges, comprising those annular ridges which are mutually adjacent, including a groove between component annular ridges having its bottom closer to the top of the rivet head than are the free ends of the component ridges. Various other formations having similar gripping characteristics may, however, be advantageously employed as equivalents of the concentric ridges.

Further features and objects of this invention are clearly set forth in the following detailed description together with the accompanying drawing, in which:

Fig. 1 is a view partly in side elevation and partly in vertical section of a preferred embodiment of the present invention.

Fig. 2 is a bottom plan view of the embodiment illustrated in Fig. 1.

Fig. 3 is a vertical detail section through a portion of a brake band together with its lining, the lining being held in place by embodiments of my invention having downwardly converging substantially frusto-conical heads.

Fig. 4 is an enlarged detail view taken on line 4—4 of Fig. 3, the rivet being shown in central vertical section.

Fig. 5 illustrates in side elevation another embodiment of this invention.

Fig. 6 is a bottom plan view of the rivet shown in Fig. 5.

Referring to the drawing and particularly to Figs. 1 and 2, at 10 is illustrated a rivet including one form of gripping means contemplated by this invention.

The rivet 10 is preferably of unitary structure and may be produced by any of the usual methods common in the rivet making art.

As component parts of the rivet 10, are the shank 11 and the head 12, the shank 11 preferably including a recess 13 in its free extremity to facilitate spread of the material of the shank 15 during the actual riveting operations, and the head 12 having a downwardly converging under-surface.

On the under-surface of, and desirably integral with the head 12, is provided gripping means. Such means preferably take the form of a plurality of annular ridges 14 concentrically arranged between the outer periphery of the shank 11 and the periphery of the head 12, and desirably being of substantially V shape to present the biting edges 14a. It will be noted that each set of concentric ridges 14, comprising those concentric ridges which are mutually adjacent, include between component ridges a groove for receiving the material to be held, the bottom of the groove 30 being closer to the top of the rivet head than are the free ends of the stated component concentric ridges.

When the rivet is in its riveted holding position, the ridges 14 bite into the material with which they become intimately associated, and, when such material is subjected to external stresses, serve to distribute the effects of same over substantially the entire area comprehended by the undersurface of the rivet head 12 rather than to merely that limited area immediately adjacent the rivet shank 11. Thereby, undue stresses at such shank adjacent area are prevented.

In Figs. 3 and 4 is shown a specialized application of the present invention wherein rivets such as 10', having downwardly converging heads 12', preferably of a general conical configuration, are utilized to fasten brake lining, such as 15, to a brake band, as at 16.

The assembly, represented by the brake lining 15 and the brake band 16, is provided with rivet receiving holes 17 configurated to form a substantially frusto-conical seat 17a, for receiving and positioning the under-surface of the heads 55

12' of rivets 10' in the material of the lining 15, the shanks 11' of the rivets passing through the opening 17 in the band 16 and being spread into holding position as at 11'a.

5 So positioned, the downwardly converging rivet head 12', exerts a force upon the material of the lining 15 in a direction substantially normal to the converging under-surface of the rivet head. Were this under-surface relatively 10 smooth, as is commonly the case, there would arise undesirable stresses in the lining material 15, and, if such material were brittle to any degree, as in the case of molded linings, such stresses would tend to split off sections of such 15 material under normal brake operation.

The gripping means forming the substance of the invention, and illustrated at 14' in the form of a plurality of annular concentric ridges similar to those shown in Figs. 1 and 2, counteract 20 the aforesaid splitting forces by biting into the material of the seat 17a and tending to draw the lining in toward the rivet shank 11' when the brake assembly is under operative stresses.

Another embodiment of gripping means is 25 shown at 21, Figs. 5 and 6, on the under-surface of the head of the rivet 20, and is another example of the various gripping formations comprehended by the present invention. The formations 21 include a plurality of arcuate projections arranged in substantially staggered relationship on the area of the under-surface of the rivet head 22.

Whereas, I have described my invention with 30 reference to specific forms thereof, it will be understood that many changes and modifications may be made without departing from the spirit of the invention.

I claim:

1. A rivet including a head and a shank, the

bottom surface of said head converging toward said shank, and gripping formations arranged on the converging surface of said head throughout the area thereof between the outer periphery of the shank and the periphery of the head, each 5 set of gripping formations, which comprises those gripping formations mutually adjacent radially of the said converging surface, including between component gripping formations a groove whose bottom lies closer to the top of the 10 said head than do the free ends of the said component gripping formations.

2. A rivet including a head and a shank, the bottom surface of said head converging toward said shank, and annular ridges concentrically 15 arranged on the converging surface of said head throughout the area thereof between the outer periphery of the shank and the periphery of the head, each set of annular ridges, comprising those annular ridges which are mutually adjacent, including between component annular ridges a groove whose bottom lies closer to the 20 top of the said head than do the free ends of the said component annular ridges.

3. A rivet including a head and a shank, the bottom surface of said head converging toward said shank, and annular ridges concentrically arranged on the converging surface of said head throughout the area thereof between the outer periphery of the shank and the periphery of the 25 head, each set of annular ridges, comprising those annular ridges which are mutually adjacent, including between component annular ridges a groove whose bottom lies closer to the 30 top of the said head than do the free ends of the 35 said component annular ridges, said annular ridges being interrupted at intervals throughout their annular extension.

FRANCIS L. SHEANE.
